UNITED STATES PATENT OFFICE

LOUIS MARIE FRANCOIS GENETY, OF PARIS, FRANCE

DEVICE FOR FEEDING EXPLOSION ENGINES HAVING AN OVER-HIGH PRESSURE OF COMPRESSION

Application filed December 27, 1929, Serial No. 416,963, and in France January 5, 1929.

The present invention relates to the feeding of explosion engines having an over-high compression, that is to say of engines in which the pressure, at the end of the compression, reaches a value too high for enabling them to work and to be normally used under full load, at low altitude, with the usual mixture of pure air.

The invention has for object an improved device the application of which to explosion engines allows such engines to work under a high compression, and which is characterized by the interposition, between the exhaust pipe line and the feeding air intake, of a conduit, in order to substitute a certain proportion of burnt gases to the atmospheric air introduced, or to add a certain proportion of burnt gases to this atmospheric air, the conduit being combined with means for obtaining the four following conditions:

1—that the burnt gases derived into the feed air should be suitably expanded.

2—that their temperature should be lowered, but only to a certain extent, for avoiding condensation of the water vapour they contain.

3—that their mixing with the air should be as intimate and homogeneous as possible.

4—that the measurement of their proportion should be exactly controlled according to the various conditions of construction or utilization of the engines.

The single figure of the accompanying drawing is a diagrammatic plan view of a form of carrying out the invention applied to a motor car engine.

The conduit must be capable to fulfill its function and in particular to satisfy the four previous conditions, either by its nature, its shape and its dimensions.

The expansion of the burnt gases must be as complete as possible, in order that their pressure should be near (above or below) atmospheric pressure. This expansion can be easily insured for instance by means of pressure reducing apparatus, such as exhaust mufflers as used on motor cars. If the exhaust pipe line is already provided with a pressure reducing apparatus, it usually suffices to admit the burnt gases on the down

side of this apparatus for obtaining a sufficient extension. The expansion can be completed by a special pressure reducing device, of any type (exhaust muffler) forming a portion of the conduit. For the same purpose, the said conduit can be also throttled at its inlet end, or at one or more other points, by means of fixed or variable diaphragms, calibrated orifices, or valves. The dimensions and shape of the conduit are preferably so chosen as to facilitate, control or complete the expansion.

In the example illustrated in the drawing, 1 designates the conduit having one end connected, as at 2, to the air inlet of the carburetor 3 of the engine 4, the other end thereof being connected, as at 5, to the exhaust pipe 6, below the muffler 7. The diaphragms 8 and 9 are respectively provided at 2 and 5 and the sections of free passage-ways 70 they allow are perfectly determined and can be fixed or adjustable.

The temperature of the burnt gases is lowered simply by the expansion. Sometimes it may be necessary to arrange, at certain points 75 of the conduit or on the exhaust pipe line, special members such, for instance, as tubes, air or water radiators, for effecting, completing or controlling the lowering of the temperature to a certain point. In any case, the 80 temperature must not be lowered below a certain degree, in order that the water vapour should not be condensed, this water vapour being one of the elements contained in the burnt gases. This condition is very important, as water vapour plays a very important part during the periods of suction, of compression and particularly during the period of combustion. The condensations of water by cooling of the burnt gases would modify 85 the water vapour content and would thus hinder the proper operation of the entire device. The best workable temperature is usually that corresponding to the state of saturating steam. The lowering and control of the temperature can also be obtained or only facilitated or completed 90 simply by the dimensions, shape, nature and position of the connecting enclosure.

The mixing of the burnt gases with the 100

feed air must be as perfect and homogeneous as possible. It can be effected in any mixing apparatus (provided with Venturi tubes or baffle plates, etc.). If the engine is provided with a carburettor, the conduit can open in the air intake of the carburettor itself, or in the air feeding pipe, and the diffuser of the said carburettor constitutes more often a very efficient and satisfactory mixer. The measurement of the proportion of burnt gases mixed with the pure air introduced is very important. It is controlled according to the pressure of compression used in the engine, so as to prevent the phenomena of detonation and self-ignition, and the abnormal rise of the temperature of the explosion.

The so-called explosion engines, of the two or four cycle type to which the device described is applicable are, to the exclusion of the others, those the adiabatic pressure of which, at the end of the compression, reaches a value higher than usual, so that if they were fed at a low altitude with the usual mixture of pure atmospheric air and carburetting agent, they could not operate under full load without presenting inconveniences, such as phenomena of detonation and self-ignition, excessive over heating, etc., and, consequently they could not be used in a practical manner. For each kind of carburetting agent and each category or type of engines, a limit pressure of compression exists, below which the mixture of pure atmospheric air and carburetting agent no longer allows of ensuring the normal operation of explosion engines. It is of course assumed that the design and construction of the engines have been judiciously carried out and that no defects exist, such for instance as hot points, capable of causing the above mentioned inconveniences at a pressure of compression lower than the said limit pressure.

The device described allows, owing to the presence of the burnt gases in the gaseous mixture, to exceed this limit pressure without being prejudicious to the proper operation of the engine.

What I claim as my invention and desire to secure by Letters Patent is:—

1. The combination with an internal combustion engine and its exhaust pipe, of a conduit affording communication between the exhaust pipe and the air intake pipe of the engine carburetor, said conduit having diaphragms mounted therein and located respectively at points adjacent the exhaust pipe and the air intake pipe, said diaphragms having apertures therein.

2. The combination with an internal combustion engine and its exhaust pipe, of a muffler connected in the exhaust pipe, a conduit having one end connected to the exhaust pipe near the discharge end of the muffler, the other end of the conduit being connected with the air intake pipe of the engine car-

buretor, and apertured diaphragms mounted in the conduit.

In testimony whereof I have signed this specification.

LOUIS MARIE FRANÇOIS GENETY.
